UNITED STATES PATENT OFFICE.

RICHARD GORNALL, OF BALTIMORE, MARYLAND, ASSIGNOR OF ONE-HALF
TO GEORGE A. DUBREUIL, OF SAME PLACE.

STORE-SERVICE APPARATUS.

SPECIFICATION forming part of Letters Patent No. 342,253, dated May 18, 1886.

Application filed February 11, 1886. Serial No. 191,609. (No model.)

To all whom it may concern:

Be it known that I, RICHARD GORNALL, of Baltimore, State of Maryland, have invented a new and useful Improvement in Store-Ser-
vice Apparatus; and I do hereby declare that the following is a full, clear, and exact de-
scription of the same.

My invention relates to store-service apparatus, and is designed more particularly for use in stores where the cashier's desk is located on the floor below or the floor above the salesroom.

In the present case I have shown the apparatus as applied to a store where the desk of the cashier is on the floor below the salesroom.

In the accompanying drawings, Figure 1 is a side elevation of my improved way, representing the position of the salesman in the upper part of the figure, and the lower floor, with the position of the cashier, the wire being broken away to allow for the enlargement of the other parts, the carrier being represented at the cashier's desk in full lines and at the salesman's counter in dotted lines. Figs. 2, 3, 4, and 5 represent details of the clutch. Fig. 6 is a detail view of the connection of the track with the standard and the operating-reel. Fig. 7 is a modification of the device to be used at the cashier's desk. Figs. 8 and 9 represent details.

The salesman's counter is represented at A, and under this counter is secured a standard, B, which is braced upon one side in any suitable manner, as shown. From the other side, extending out horizontally a short distance, and curving to a vertical position, extends a metal track, C, which passes down through an opening in the floor to a suitable distance below the ceiling of the room beneath. The track is composed of flat bars set on edge, of any suitable size and weight. The standard B is slotted at 1 2 3, as shown. An adjustable plate, a, is adapted to be secured adjustably to the said standard by bolts passing through the slots therein. This plate a carries a lug, 4, the opening in which registers with that in a corresponding lug, which is secured suitably

to the end of the track C, and this end of the track is thus secured to the standard by bolts 50 passing through openings in the lug. By these means it will be seen that the end of the track may be moved adjustably up or down on the standard by means of the plate a, and that it may be turned on its connecting-pin to any 55 angle desired. After the track has been set at a proper angle it is supported in that position by means of a screw, 5, which passes through the lug 6 and bears against the plate a, thus taking up the strain. To the opposite end of 60 the track C, which is in the room beneath, one end of the wireway is attached. This wire extends from the end of the track, either in an inclined or vertical plane, to the cashier's desk, being shown inclined in the figure and 65 attached to the track C', which forms a continuance of the way and curves upward, as shown. This curved sectional track C' forms part of the frame D, which consists of a vertical bar, b, having cross pieces or straps c c', 70 supported upon a standard, D'. The frame is movable on said standard and is provided with a pulley between it and the standard at its lower end, and a pulley between the end of the strap c' and the standard, near its center, 75 whereby all strain from the curved track and the tension on the wireway is taken up. Cords 5 and 6 are provided for lowering and raising this frame, said cords being arranged in a well-known manner.

In Fig. 7 I have shown a modified view of the raising and lowering mechanism. In this figure the curved bar b', heretofore described, instead of being a part of the moving frame, is moved directly by means of a cord connected thereto and passing over a pulley, as shown, said bar passing through guide-bars 15, held on either side of the bar in the frame 16, secured to a suitable bracket. Instead of having a raising and lowering device at this 90 end of the way, it is obvious that the wire may be secured to a curved track extending downwardly—such as that described in an application filed of even date herewith, Serial No. 191,608—or the way may be secured permanently to a suitable eyebolt.

The cash or parcel carrier is shown at E. It is composed of a suitable box pivoted to rods 8, which rods pass upon either side of the track and have a large pulley, 9, upon one side of the track and a smaller pulley, 10, supported upon a small projection upon the other side of the track. From the rods 8, at right angles thereto, project similar rods, 12, with an angular projection upon their ends, having likewise pulleys upon either side of the track, so that the frame, which is composed of these rods, and consequently the carrier, is steadily held upon the track, and there is but little vibration thereupon. The rods 8 are of such length, and the cash or parcel carrier is pivoted so freely between them that it keeps in vertical position, with its open side up in all the varying positions that the carrier-frame assumes.

In order to adapt the carrier shown with the special form of raising and lowering devices and curved track at the cashier's desk, I have provided a pivoted hook upon the forward end of the carrier, which is adapted to engage in notches in the face of the curved track as the carrier mounts upon it from the impetus given to it by being impelled upon the way. A pin projects from the head of the hook d, and when it is desired to release the carrier from the notched face of the track C' the frame D is raised until the tail-piece of the kicker e strikes against the stud f on the standard, and the forward end of the kicker comes in contact with the pin on the hook, which it lifts out of the notch and allows it to descend by its own weight, and the impulse given by the curve of the track carries it along the way.

I will now describe the clutch mechanism for lowering the carrier from the upper floor to the floor below and impelling it upon the way to the cashier's desk, and for taking the carrier from the lower floor and elevating it to the upper. The carrier-frame has a pivoted end piece, g, which is wedge-shaped on its end and slotted a little to the rear of the end. The carrier is connected to a clutch mechanism by means of this end piece, and is carried along therewith. The clutch consists of a frame, F, having a pulley, h, upon one side, and a similar pulley, i, directly opposite on the other side, of the track. To an eye projecting from one end of the clutch a winding-cord is attached, which is secured to a reel at the end of the curved track under the counter, within convenient reach of the salesman. The reel is provided with a suitable pawl-and-ratchet mechanism, and is adapted to be operated in the ordinary manner.

A post, h', projects from one of the inside corners of the clutch-frame, and in this post, which is hollow, is a latch, i', the latch being held under tension by a spring-plate, k, bearing upon the top thereof, said spring being secured to its opposite end upon a post, k'.

The latch has an inclined face and enters the recess k², which is formed in one corner of the clutch, and into this recess the end piece of the carrier is adapted to enter and to be locked therein by the latch registering with the slot in the end thereof. In this locked position the clutch and the carrier are started down the way from the salesman's counter, being held under control of the salesman by means of the reel and cord, as hereinbefore described. The carrier and clutch descend the way thus locked until the forward end of the clutch meets the projection l upon the lower end of the vertical track, when the carrier is released from the clutch by means of a depending arm on a lever, n, striking the projection l, the said lever n having a finger upon its forward end, which bears against a projection, o, on the latch i', which thus draws the end of the latch out of the recess k², and the carrier, being in advance of the clutch and freed therefrom, is impelled by the momentum obtained by its vertical descent along the way to the cashier's desk. A stop, p, projects from the side of the track a short distance below where the carrier is released from the clutch, and this comes into contact with the rear wall of the clutch-frame and stops it at this point, as shown in detail figures. The front end of the clutch-frame is recessed in order to pass over this stop, and the carrier-frame is also, as shown in Fig. 9, adapted to pass this stop. The pulley h is grooved deeply, as shown in the detail figure, in order that it may pass the projection l, and the pulley 10 of the carrier is also grooved in like manner.

When the cashier is ready to return the carrier, he gives to it an impulse by hand, or by means of raising and lowering devices heretofore described or referred to, sufficient to carry it over the wireway and the track, which forms a continuance of the same, to the clutch which is at rest against the stop. The end piece, g, registers with the recess k², and is thus locked in place and ready to be elevated to the floor above, and this is done by the salesman winding upon the cord attached to the clutch, and as he continues to wind the clutch and carrier will rise up the vertical part of the track to the position shown in dotted lines, which will place the carrier into the position immediately under a suitable opening, which may be made in the counter to receive it.

Any suitable signaling apparatus may be used, if desired, by the cashier to notify the salesman that the carrier is ready to be elevated; but this will hardly be found necessary, as the salesman can see it at a glance through the opening in the floor.

Instead of the track curving at the upper part, as shown, and having a horizontal portion, it may stop at the curve, or it may be carried up vertically, but the form shown is the form preferred. Suitable guiding pulley or pulleys may be used, as shown, for the winding-cord, if found necessary.

I do not limit myself to the particular construction of the carrier, as this may be changed indefinitely. It will only be necessary that some means be connected therewith to adapt it to be secured to the clutch.

In order to control the descent of the carrier and clutch from the upper to the lower story without rendering it necessary for the salesman to keep hold of the handle of the reel, 10 I have provided the device shown in Fig. 8. This represents a detail view of the connection at the upper end of the track beneath the counter. Upon the end of the reel-shaft, opposite the handle, a gear-wheel, 16, is loosely 15 supported, which carries a pawl, 17, engaging with a ratchet, 18, secured to the shaft. The gear 16 is in mesh with a pinion, 19, on the shaft of a fan, 20. This fan is composed of a hub having suitable spokes or arms, the fans 20 proper being loosely supported, so as to slide thereon. Light springs upon the ends of the arms bear upon the fans. The result of the use of the fans is to allow the carrier to descend gently the vertical part of the track, and the 25 result of the particular construction described is to cause the fans to act as a governor, moving by centrifugal force nearer the ends of their arms under increased weight, thereby serving to check uniformly the carrier, whether it contains much or little.

Instead of the form of retarding device shown, modifications, such as shown in application filed by me of even date herewith, may be substituted.

35 I claim as my invention—

1. In a store-service apparatus, the combination, with a way extending from one floor to the one below, of a carrier mounted thereon, and a clutch mechanism moving on the way 40 under the control of the salesman, detachably connected to said carrier and adapted to lower and raise it to or from the floor above, substantially as described.

2. In a store-service apparatus, the combination, with a way extending from one floor to the floor below, of a carrier mounted on said way, a clutch mechanism moving on the way under the control of the salesman, detachably secured to said carrier, and means, substantially as described, for releasing said carrier from said clutch mechanism and stopping said clutch, whereby the carrier continues on the way alone to the cashier's desk, substantially as described.

55 3. In a store-service apparatus, the combination of a metal track extending from the upper to the lower floor, the wireway extending from the end of said track to the cashier's desk, a carrier mounted on said way, clutch 60 mechanism moving on the way, detachably connected with said carrier, means for lowering and raising said clutch under the control of the salesman, and means for releasing the carrier from the clutch mechanism, whereby 65 it is impelled to the cashier's desk, substantially as described.

4. In a store-service apparatus, the combination of a curved track, the wireway extending from the lower end of said track to a curved section of track at the cashier's desk, 70 a carrier mounted on the way and detachably connected to a clutch mechanism moving on the way under the control of the salesman, said clutch mechanism being adapted to be lowered and raised, means for releasing said carrier 75 from said clutch, means for raising said clutch, and mechanism for raising and lowering the track at the cashier's desk to return the carrier to the position of the clutch, the parts being constructed and operating substantially 80 as described.

5. In a store-service apparatus, the combination of a track from one floor to the floor below having a carrier mounted thereon detachably connected to a clutch mechanism 85 adapted to be raised and lowered by the salesman, said clutch mechanism consisting of a frame having suitable pulleys for its easy passage over the track, a recess adapted to receive the end piece of the carrier, a locking 90 mechanism to hold the same thereto, and mechanism, substantially as described, adapted to be actuated by a projection on the track at the end of the vertical part thereof, to release the carrier from said clutch mechanism, 95 substantially as described.

6. In a store-service apparatus, the combination, with a way extending from one floor to the floor below, of a carrier mounted thereon consisting of a receptacle pivoted upon projecting arms, pulleys on said arms bearing on either side thereof, and arms projecting at right angles to the first set and provided also with pulleys at the other end, and mechanism for raising and lowering the said carrier, substantially as described.

7. In a store-service apparatus, the combination of a way, a carrier mounted thereon having pivoted catch, the lowering and raising device under the control of the salesman, and 110 a lowering and raising mechanism at the cashier's desk consisting of a curved rod having a notched face, substantially as described.

8. In a store-service apparatus, the combination of a fixed stationary way between the 115 upper and lower floors of a store, a carrier mounted thereon, a raising and lowering device moving on the way detachably connected to said carrier under the control of the salesman, and mechanism, substantially as described, adapted to permit the gradual descent of the carrier, substantially as described.

9. In a store-service apparatus, the combination of a stationary way, a carrier mounted thereon, a raising and lowering device detachably connected to said carrier under the control of the salesman, and a fan in connection with the operating-reel, whereby the descent of the carrier is made gradual and under the control of the said fan, substantially as 130 described.

10. In combination, a stationary way, a car-

rier mounted thereon, a raising and lowering device detachably connected to said carrier under the control of the salesman, a device for permitting the gradual descent of the carrier under all condition of weight, consisting of the fan having sliding connections under spring-tension, substantially as described.

In testimony whereof I have signed my name to this specification in the presence of two subscribing witnesses.

RICHARD GORNALL.
